Primary Examiner — David G Muller*Assistant Examiner* — Nathan M Johnston(74) *Attorney, Agent, or Firm* — Calfee, Halter & Griswold LLP(57) **CLAIM**

The ornamental design for a wall mounted dispenser cabinet, as shown and described.

DESCRIPTION

FIG. 1 is a perspective view of a wall mounted dispenser cabinet of the new design;

FIG. 2 is a top plan view of the wall mounted dispenser cabinet of FIG. 1;

FIG. 3 is a front elevational view of the wall mounted dispenser cabinet of FIG. 1;

FIG. 4 is back elevational view of the wall mounted dispenser cabinet of FIG. 1;

FIG. 5 is bottom view of the wall mounted dispenser cabinet of FIG. 1;

FIG. 6 is a left side elevational view of the wall mounted dispenser cabinet of FIG. 1; and,

FIG. 7 is a right side elevational view of the wall mounted dispenser cabinet of FIG. 1.

The broken line showing of wall mounted dispenser cabinet is included for the purpose of illustrating portions of the article and forms no part of the claimed design.
